UNITED STATES PATENT OFFICE.

ALFRED A. LANTERNIER, OF LIMOGES, FRANCE.

DESIGN FOR A DISH.

SPECIFICATION forming part of Design No. 24,544, dated August 13, 1895.

Application filed May 14, 1895. Serial No. 549,324. Term of patent 7 years.

To all whom it may concern:

Be it known that I, ALFRED A. LANTERNIER, a citizen of the Republic of France, residing at Limoges, France, have invented and produced a new and original Design for a Dish, of which the following is a specification.

The leading feature of my design consists of a dish of essentially the configuration shown in the accompanying drawings.

In the drawings, Figure 1 is a top or face view of a dish embodying my design. Fig. 2 is a vertical section of a portion of the same on line 22 of Fig. 1.

A represents the central panel of the dish,

and B the rim or border therefor, which rim or border follows the contour of the central panel A, and has undulations *a* and comparatively larger undulations *b* extending around the rim throughout the entire extent thereof and in a transverse direction thereto. 15 20

What I claim is—

The design for a dish, substantially as shown and described.

ALFRED A. LANTERNIER.
